UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

AIR-LIFT PUMP.

Application filed December 31, 1923. Serial No. 683,581.

This invention relates to air lift pumps, and more particularly to foot pieces therefor.

It has for its object to provide an improved foot piece. A further object is to provide a foot piece having a plurality of parts with improved means for assembling and disassembling the same.

In the accompanying drawings I have shown for purposes of illustration one form which my invention may assume in practice.

In these drawings,—

Fig. 1 is a vertical section of the foot piece. Fig. 2 is a section on line 2—2 of Fig. 1.

Fig. 3 is a vertical partial section on line 3—3 of Fig. 1.

In my improved device I propose to use a base 1 having upwardly directed openings 2 and 3 and a downwardly directed opening 4 formed in a downwardly projecting boss 5. A third opening 6 is at the upper end of a vertical passage which has communication with the opening 4 as by a transverse passage 7. Mounted within the opening 2 is the usual fluid supply pipe 8 which allows fluid to flow into the base 1 and thence upwardly around a mixing tube 9 which projects upwardly through the opening 4 in the boss 5 and is held therein by threads 30 or other suitable means. Where the material used in the construction of this device is lead, the mixing tube 9 and base can be burned so that it will have an integral connection with the base 1. More specifically,

this tube comprises a cylindrical tube having annular portions 10 on the lower end thereof which are disposed within the opening 4 while a flange 11 abuts against the lower surface of the boss 5. A bore 12 extending substantially throughout the length of the mixing tube is plugged at the bottom as at 13 to prevent escape of actuating fluid and is closed at the other end by a conical plug 14. Inclined discharge ports 15 extend outwardly from the bore 12 and allow escape of actuating fluid into the surrounding fluid contained within the Venturi pipe 16. The latter will have communication at its lower end with the opening 3 and at its upper end with the usual riser pipe (not shown). Actuating fluid, preferably air, is admitted through a supply pipe 17 having communication with the opening 6 from which it flows through passage 7, around an annular chamber 18 formed between the spaced por-

tions 10 on the mixing tube and through openings 19 therein.

In the operation of this device, liquid to be pumped flows down the pipe 8 into the hollow base 1 and up into the Venturi pipe 16 to a level which will correspond to the natural level of the liquid being pumped. When pumping is started, the liquid within the pipe 16 surrounding the mixing tube 9 will be aerated by fluid flowing in through pipe 17, opening 6, passage 7, and through the lateral openings 19 in the lower portion of the tube 9 which have communication with the annular space disposed between the portions 10. An additional feature of my construction is that the mixing tube 9 may be readily downwardly removed from the base 1 without disturbing any of the remaining portions of the device. Another feature to be noted in this connection is that when the tube is removed, the inlet ports and the opening 4 are left entirely open so that any foreign matter accumulated in these parts may be readily removed.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. An air lift foot piece comprising a casing with an inlet for the material to be pumped and an outlet for discharging the same, said casing being further provided in the lower side thereof with a threaded opening surrounded by an abutment surface, a hollow mixing tube adapted for insertion in said opening and having adjacent but spaced from its lower end a threaded portion adapted to cooperate with the threads of said opening and nearer its end an abutment portion adapted to cooperate with said abutment surface, and between said abutment portion and said threaded portion a portion substantially smaller than said threaded portion having therein an opening communicating with the interior of said tube, and an inlet for the actuating fluid opening into the space below said threaded portion.

2. An air lift foot piece comprising a cas-

ing with an inlet for the material to be pumped and an outlet for discharging the same, said casing being further provided in the lower side thereto with a threaded opening surrounded by an abutment surface, a hollow mixing tube adapted for insertion in said opening and having adjacent but spaced from its lower end an enlarged annular threaded portion adapted to cooperate with the threads of said opening and nearer its end an enlarged abutment portion adapted to cooperate with said abutment surface, and between said abutment portion and said threaded portion a reduced portion provided with an opening communicating with the interior of said tube, and an inlet for the actuating fluid opening into the annular space below said threaded portion.

3. An air lift foot piece comprising a casing with an inlet for the material to be pumped and an outlet for discharging the same, said casing being further provided in the lower side thereof with a threaded opening surrounded by an abutment surface, a hollow mixing tube adapted for insertion in said opening and having adjacent but spaced from its lower end an enlarged annular threaded portion adapted to cooperate with the threads of said opening, and nearer its end an enlarged abutment portion adapted to cooperate with said abutment surface and an enlarged annular portion substantially filling said threaded opening transversely, and between said abutment portion and said annular portion an opening communicating with the interior of said tube, and an inlet for the actuating fluid opening into the annular space below said threaded portion.

4. An air lift foot piece comprising a casing with a downwardly directed passage serving as an inlet for the material to be pumped and a communicating upwardly directed opening for communication with a riser pipe, said casing also having a threaded bore for the reception of a mixing tube alined with said upwardly directed opening and having a downwardly extending pumping fluid supply duct opening into said bore between its ends, and a mixing tube comprising an upper apertured discharge portion and a communicating lower pumping fluid receiving portion, the latter having a reduced portion provided with a fluid supply opening opening laterally and having above said reduced portion a threaded portion cooperating with said threaded bore and at its lower end a portion forming a tight joint with said casing, said pumping fluid supply duct communicating with the space below said threaded portion.

5. An air lift foot piece comprising a casing with an inlet for the material to be pumped and an outlet for discharging the same, said casing being further provided in the lower side thereof with an opening sur-

rounded by an abutment surface, a hollow mixing tube adapted for insertion in said opening having adjacent to but spaced from its lower end spaced annular portions at opposite sides of a portion of lesser diameter, the upper one of said portions and said opening being adapted to cooperate to form a seal and the lower one of said portions and said opening being adapted to cooperate to provide a guide against tilting, said mixing tube having at its bottom means cooperating with said abutment surface to effect a seal, and an inlet for the actuating fluid opening into the annular space provided by said portions.

6. An air lift foot piece comprising a casing with an inlet for the material to be pumped and an outlet for discharging the same, said casing being further provided in the lower side thereof with an opening surrounded by an abutment surface, a hollow mixing tube adapted for insertion in said opening having in spaced relation to its lower end means adapted to cooperate with the bore of said opening to effect a seal and having at its lower end means adapted to cooperate with said abutment surface to effect a seal and having intermediate said parts a portion of reduced diameter containing a fluid supply opening, and an inlet for the actuating fluid opening into the space between said parts which surrounds said portion of reduced diameter.

7. A foot piece for air lift apparatus comprising a casing and a mixing tube, said casing having an inlet for the material to be pumped, an outlet for discharging the same, and an opening adapted to receive said mixing tube by insertion therein, said mixing tube having spaced enlargements adapted to cooperate with said opening to form a chamber and said tube being provided with means for supplying fluid to said mixing tube from said chamber, and an inlet for the actuating fluid opening into said chamber.

8. A foot piece for air lift apparatus comprising a casing with an inlet for the material to be pumped and an outlet for discharging the same, said casing being further provided with a vertical opening, a mixing tube having an annular groove on the exterior thereof adapted to cooperate with said opening to form a passage, and means provided in said base and mixing tube including said passage for supplying actuating fluid to said mixing tube.

9. An air lift foot piece comprising a casing with an inlet for the material to be pumped and an outlet for discharging the same, said casing being further provided with a vertical opening, a mixing tube having spaced enlargements adapted to engage said vertical opening whereby said tube may be supported in said opening or removed through the lower end of said opening, and means including the

chamber defined by said enlargements for supplying actuating fluid to said mixing tube.

10. An air lift foot piece comprising a casing with an inlet for the material to be 5 pumped and an outlet for discharging the same, said casing being further provided with a vertical opening, a mixing tube having an enlargement adapted to threadedly engage

said opening and a second enlargement on said mixing tube adapted to cooperate with 10 said vertical opening and first enlargement to form a chamber, and means including the said chamber for supplying actuating fluid to said mixing tube.

In testimony whereof I affix my signature.
HALBERT B. HALVORSEN.
